SAMPLING DEVICE

James M. McManus, Jersey City, N. J., assignor
to Western Electric Company, Incorporated,
New York, N. Y., a corporation of New York

Application May 3, 1934, Serial No. 723,715

2 Claims. (Cl. 193—31)

This invention relates to sampling devices and more particularly to devices for sampling the product of a machine producing a sequence of discrete articles such as a punch press or the like while in operation without interruption.

In a punch press as is well known, a cooperating punch and die are used to cut articles usually from sheet material by a shearing action between the punch and die. In time the two cooperating tools wear and the shearing effect becomes less efficient until the burr left on the work produced becomes too large, when the press must be stopped and the tools repaired or replaced.

One object of the invention is to provide a device applicable to any machine such as an article forming press which produces a sequence of discrete articles combined with means to guide or to carry the articles away from the machine along a predetermined normal path, the device being operable at will to be interposed between the machine and the article guiding or removing means to divert one or more articles at will from their normal path for inspection, testing or analogous purposes.

With the above and other objects in view, one embodiment of the invention contemplates a machine for producing disconnected articles in a continuous sequence and discharging them along a predetermined path, which is provided with means operable at will to divert one or more articles from the predetermined path for examination or test without otherwise interfering with the normal operation of the machine. The machine may be for example an ordinary punch press having a female die supported on the bed plate of the press and a coacting punch mounted on the reciprocating ram or cross-head. Sheet material may be fed between the punch and die advancing between successive strokes of the punch. A stacking or magazining device is located under the bed plate to receive punchings from the die and assemble or stack the same in co-oriented pluralities. The stacking device comprises a chute leading from the under face of the die to the stacker proper. The sampling device characteristic of the invention is interposable between the stacking chute and the die and includes a swinging gate or other means to divert away from the chute an article issuing from the die to be caught manually or otherwise for inspection.

Other objects and characteristic features of the invention will appear from the following detailed description of one embodiment thereof taken in connection with the accompanying drawings in

which like reference numerals are applied to identical parts in the several figures and in which

Fig. 1 is a broken view in side elevation and partly in section of a punch press having a stacking device embodying the invention;

Fig. 2 is a similar view thereof in front elevation;

Fig. 3 is a detached broken plan view of the stacking device alone, and

Fig. 4 is a similar view thereof in side elevation.

As herein disclosed the invention is embodied in a sampling device adjoined to a stacking or magazining apparatus attached to a punch press. The punch press is an old and well known machine the details of construction and operation of which are familiar and not pertinent to the invention. To avoid unnecessary complexity in the drawings therefor, parts of the die 20 and of the bolster or bed-plate 21 of the press, which supports the die, are the only parts of the machine shown. The die 20 has a vertical perforation 22 adapted to coact with a corresponding punch not shown to cut laminar blanks or punchings one at a time from a strip or sheet of material fed step by step over the top surface of the die. Successive blanks are pushed by the punch through the perforation 22 into the stacking device below. The blanks here considered are of an elongated rectangular C-shape. The die 20 is further provided with a pair of yieldable spring pressed detents 23 housed in corresponding bores in the body of the die to keep the blanks from falling through the die or issuing therefrom except under compulsion by the punch.

The stacking device comprises a pair of vertically disposed mutually parallel supporting and guiding rods 30 whose upper ends are threaded and screwed into corresponding tapped holes in the under face of the die and supported thereby. The lower ends of the rods 30 are rigidly spaced apart and held in a yoke 31 perforated to receive the rods which are threaded and locked in place in the yoke by nuts 32. An otherwise idle portion 33 of the rods 30 is formed with a hexagonal cross-section to facilitate screwing the rods into the die, while the rods above this portion are preferably circular in cross-section to act as guide slides as hereinafter described.

A pair of upper slide blocks 34 and a pair of lower slide blocks 35, each appropriately perforated, are mounted to slide on and be guided by the cylindrical upper parts of the rods 30. These four slide blocks 34 and 35 are vertically spaced apart and held rigidly by being attached by weld-

ing or otherwise to a substantially rectangular back plate 36.

Four mutually substantially parallel and conveniently curved guide rails 37 form a skeleton trough to receive and guide punchings or blanks issuing from the bottom of the perforation 22. These rails 37 are attached rigidly at their upper ends either to the blocks 34 and 35 or to the back plate 36 as by screws 38. The screws 38 are omitted in Fig. 2 for simplicity. The trough 37 is part of a stacking device for collecting blanks or punchings into regular groups or piles. The fate of the blanks after entering the trough 37 is not relevant to the present invention and so only the upper part of the trough is shown. The trough as a whole, however, moves up and down with the slide blocks 34 and 35 as hereinafter disclosed. A blank 39 is shown in position in Fig. 3 entering the top of the trough and is also indicated in dotted lines in Fig. 2.

The upper link 40 of a vertically disposed toggle is pivoted at 41 to a lug dependent from the lower side of the back plate 36.

The lower link 42 of the toggle is pivoted at 43 to a lug upstanding from the fixed yoke 31, and at 44 to the upper link. The lower link 42 is generally T-shaped. One horizontal arm 45 (Fig. 2) is perforated at its outer extremity for attachment thereto of the upper end of a tension spring 46, the lower end of which is attached adjustably, as by a thumbscrew and slide 47, 48, to the yoke 31. The other horizontal arm 49, shown as broken off, carries a handle not shown, or is attached to a treadle not shown or otherwise adapted for convenient actuation. The arm 49 is also formed with an integral stop shoulder 50 adapted to abut against the link 40 to prevent overthrowing of the toggle to the right (in Fig. 2).

When the arm 49 is pressed down the parts will assume the positions indicated in dotted lines in Fig. 2. A pivotable latch 51 pivoted to the yoke 31 is provided to coact with a pin 52 mounted in the link 42 to hold the parts in the dotted line position for as long as may be desired against the tension of the spring 46.

The stacker trough 37 is made thus movable to permit of actuating the sampling device at will. The sampling device proper comprises a pair of supporting members 53 mounted on the upper ends of the rods 30 and held in place rigidly against the under face of the die 20 by being clamped between the under face of the die and shoulders formed on the rods 30. An inverted U-shaped front plate 54 is attached to the front faces of the members 53 as by screws 55. The screws 55 are omitted in Fig. 2 for clarity.

A swinging gate 56 having a broad shallow U-shaped cross-section, is positioned in the U of the plate 54 and is pivotally mounted on pins 57 carried in the ends of the plate 54. A coil spring 58 supported on one of the pins 57 and having one end anchored in the plate 54 and the other in the gate 56 tends to swing the gate from the position shown in Fig. 1 to that shown in Fig. 4. When the parts are in the positions shown in Fig. 1, the top of the gate rests against the blocks 34 which hold the gate against the urge of the spring. A stop block 59 is mounted on the plate 54 and lo-

cated and proportioned to prevent the gate from swinging further than shown in Fig. 4.

When the machine is operating normally a continuous sequence of punched blanks passes down through the perforation 22 in the die 20. These blanks enter the trough 37 and are guided away thereby for further treatment or other disposal, e. g. to be collected into regular stacks.

When it is desired to take a sample of the blanks, to determine by inspection thereof the condition of the punch and die or for any other purpose, the arm 49 is depressed. This actuates the toggle 42-40 to draw down the back plate 36 and therewith the blocks 35 and 34 and the trough 37 as indicated in dotted lines in Fig. 2 into the position shown in full lines in Fig. 4. As the blocks 34 slide down they cease to support the top of the gate 56 against the urge of the spring 58 and the gate swings into the position shown in Fig. 4.

So long as the gate is in the position of Fig. 4, blanks dropping from or pushed out of the die 20 are diverted from their normal path and may be caught as they fall from the gate in the operator's hand, or in a box or basket, or in any other convenient receptacle.

The bar 49 may be held down by hand as long as desired or locked down by the latch 51.

By returning the bar 49 to horizontal, the conditions shown in full lines in Fig. 2 are restored and the apparatus then continues to function normally.

The invention is herein disclosed as embodied in a device attached to a punch press having a delivery chute to receive work from the die. The invention is however not limited to application to such a machine. Wherever a machine delivers a sequence of discrete articles into means for guiding the articles away along a predetermined normal path, the invention may find application in a device interposed between the machine proper or a delivery member thereof and the guiding means to divert articles at will from their normal predetermined path. Hence the invention is applicable to a large variety of machines and processes.

The embodiment of the invention herein disclosed is illustrative merely and may be modified and departed from in many ways without departing from the spirit and scope of the invention as pointed out in and limited only by the appended claims.

What is claimed is:

1. In an article forming press having a die, a support attached to the die, means on the support movable into one position to normally receive articles from the die and movable into another position, and means, caused to become operative by the receiving means in moving, to interpose between the die and the receiving means to divert articles from the receiving means.

2. In an article forming press having a die, a support attached to the die, means on the support movable into one position to normally receive articles from the die and movable into another position, and a gate, caused to become operative by the receiving means in moving, to interpose between the die and the receiving means to divert articles from the receiving means.

JAMES M. McMANUS.
